(57) **CLAIM**

The ornamental design for a flower shaped flower lollipop sculpture, as shown and described.

DESCRIPTION

FIG. 1 is a front, top, and left side perspective view of a flower shaped flower lollipop sculpture according to the present invention;

FIG. 2 is an enlarged view of area “2” shown in FIG. 1; FIG. 3 is a front view of the flower shaped flower lollipop sculpture of FIG. 1;

FIG. 4 is a left side view of the flower shaped flower lollipop sculpture of FIG. 1;

FIG. 5 is a top view of the flower shaped flower lollipop sculpture of FIG. 1; and,

FIG. 6 is a bottom view of the flower shaped flower lollipop sculpture of FIG. 1.

The short-short-long dashed broken lines indicate cutoff boundaries for enlarged detail portion views and form no part of the claimed design.

1 Claim, 5 Drawing Sheets
